UNITED STATES PATENT OFFICE.

CHARLES F. GAUNT, OF BIRMINGHAM, ENGLAND.

MEDAL-RIBBON MOUNT.

Application filed March 10, 1921. Serial No. 451,363.

To all whom it may concern:

Be it known that I, CHARLES FREDERICK GAUNT, of the city of Birmingham, England, a subject of the King of Great Britain, have invented certain new and useful Improvements in Medal-Ribbon Mounts (for which I have filed an application in England April 21, 1917, Patent No. 115,069); and I do hereby declare that the following 10 is a full, clear, and exact description thereof.

This invention has reference to medal ribbon bars or mounts and consists of the herein described improved method of, or means for, permanently attaching a medal ribbon 15 or medal ribbons thereto.

It has previously been proposed for a medal ribbon bar to be formed of trough section with upstanding edges and for the ribbon when folded round the front of the 20 bar and with its ends in the trough to be secured by a wire clip or by a second removable bar secured in the trough by screws or other suitable means, such as by flat headed studs which pass through slots in the 25 removable bar in the trough and it has also been proposed for these studs to be engaged by a split pin at the back. The act of placing the removable bar over the ends of the ribbon or ribbons in the trough has the effect 30 of drawing the ribbon tightly round the front of the ribbon bar and securing the ribbon thereto as when the ribbon bar is fixed the ends of the ribbons are firmly clamped in the trough between the ribbon bar and the 35 removable bar. It has also been proposed for the sides of the trough section ribbon bar to slope inwardly and for the removable bar or keep to be made of corresponding shape with springy sides bent inwardly towards 40 each other and designed to fit within the body and sloping springy sides of the ribbon bar and to secure the ends of the ribbon therein by clamping them between the sloping sides of the ribbon bar and removable 45 bar or keep. Moreover it has been proposed for the removable bar or keep to be furnished with upwardly projecting prongs like the prongs of a paper fastener adapted to pass through the garment and to be opened 50 out at the back of the same so as to secure the ribbon bar thereto.

For the purpose of my invention a medal

ribbon bar consists essentially of two bars namely a front bar and a back bar. The front bar is of elongated form with upstanding parallel side edges so that the bar is of shallow trough section. The back bar is a parallel sided flat section bar the width of which is slightly less than the inside width of the trough of the front bar and the thickness of this back bar is slightly less than the depth of the upstanding sides of the front bar. In fixing the ribbon or ribbons to the ribbon bar, the ribbon is or the ribbons are folded round the front of the front 60 bar and the ends of the ribbon are folded over the sides of the trough and into the interior of the top of the ends of the ribbon or ribbons and there fixed by press tools or the like which close the side edges of the trough firmly on to and around the edges of the back bar and also fixing the ribbon or ribbons to the compound bar. The back bar is preferably fitted with a brooch pin and catch or other suitable means for attachment 65 of the medal ribbon bar to a coat or other garment.

For full comprehension however of my invention reference must be had to the accompanying drawings in which similar 70 reference characters indicate the same parts, and wherein—

Figure 1 is a cross sectional isometrically projected back view of a medal ribbon bar constructed in accordance with this invention shewing also some medal ribbons 75 fixed thereto;

Figure 2 is a cross sectional elevation of the back and front bars of the same separated the front bar being shewn in the 80 shape which it has before its side edges are closed down on to the ribbon and back bar;

Figure 3 is a cross sectional elevation of the same before the side edges of the front bar are closed down on to the ribbon and 85 back bar;

Figure 4 is a cross sectional elevation of a modified form of front bar for the ribbon bar, and

Figure 5 is a cross sectional isometrically 100 projected back view of a modified form of the back bar.

Referring to the drawings it will be seen that the medal ribbon bar consists essentially

of two bars namely the front bar A and the back bar B. The front bar A is of an elongated form having two upstanding parallel side edges marked respectively 1 5 and 2 and the back bar B is also parallel sided and of flat section but of a width slightly less than the width inside the trough that is the width between the sides 1 and 2 of the front bar A. The length of the bars 10 A and B depends upon the width of the ribbon or of the various ribbons which it is required to hold.

The method of fixing the ribbon or ribbons to the combined ribbon bar is as follows: 15 A short piece of the ribbon 3 that is long enough to pass round the ribbon bar and over the upstanding side edges 1, 2 of the same to lie against the back of the ribbon bar is folded over the front and sides 20 of the trough and into the interior of the same as shewn in Fig. 3 and there the ends are held by placing the back bar B on them in the trough as shewn in Fig. 3, so that the ends of the ribbon or ribbons are 25 clamped between the two plates the ribbon being fairly tight. Now by press tools or the like the upstanding side edges 1, 2 of the trough enclosed by the ribbon or ribbons are pressed down firmly on to and 30 around the edges of the back bar B as in Fig. 1 thereby at one operation securing the back bar B in the trough of the front bar A and also fixing the ribbon or ribbons to the compound bar and drawing the ribbon 35 or ribbons tightly round the front bar. The back bar B is furnished with suitable means for the attachment of the medal bar to a coat or other garment. For instance the back bar B may be fitted with a brooch pin such as 4 jointed at one end 5 to the back bar B and at the other end arranged 40 to engage under a hook like catch piece 6 formed on or fixed to the back bar B.

In a modified form of the front bar A 45 one of the upstanding edges say that edge 2 is bent over into the trough as in Fig. 4 ready to overlap the edges of the back bar B and the ribbon or ribbons before the back bar is placed in the trough and then both edges 1, 2 are finally closed down on to the back bar and ribbon or ribbons as afore said.

Or, as a further modification, the back bar B may have one or more pairs preferably 50 two pairs of upwardly projecting flat pliable sheet metal prongs 7, 8 which project from the back of the back bar B and are adapted to pierce the coat or other garment and to be bent over on the inside of the same to 55 attach the compound ribbon bar thereto. These prongs 7, 8 can be made separately and fixed to the back of the back bar or they can be made in a piece therewith as lateral projections of the blank (as indicated by the dotted lines in Fig. 5) which

are afterwards bent back on to the back of the plate B and bent upwardly as shewn by the full lines in this figure.

It will be seen that the front bar A and the back bar B are both of about the same 70 length. In order to facilitate the placing of the back bar B in its correct position in the trough of the front bar A so that the ends are level the front bar A is at one end preferably made with a small upturned tongue 75 or tang such as 9 forming a stop or an abutment for one end of the back bar B to bear against.

What I claim is as follows:

1. A medal ribbon bar consisting of a 80 sheet metal front bar of channel cross section, a sheet metal back bar located in position between the flanges of the front bar and bearing flat against said last mentioned bar, a ribbon stretched over the front face 85 of said front bar and having its ends extending over the flanges and interposed between the bearing faces of the two bars, said flanges being bent down upon and overlapping said back bar for the purpose of retaining the latter and the ribbon in place, means located at opposite ends of the front bar for preventing endwise displacement of the back bar thereon and means carried by the back bar for attachment to a garment. 95

2. A medal ribbon bar consisting of a sheet metal front bar of channel cross section, a sheet metal back bar located in position between the flanges of the front bar and bearing flat against said last mentioned bar, a ribbon stretched over the front face of said front bar and having its ends extending over the flanges and interposed between the bearing faces of the two bars, said flanges being bent down upon and overlapping said back bar for the purpose of retaining the latter and the ribbon in place, a rearwardly extending tongue formed integrally with the front bar at each end thereof and adapted to engage the adjacent end 100 of the back bar for the purpose of preventing endwise displacement of the latter. 105

3. A medal ribbon bar consisting of a sheet metal front bar of channel cross section, a sheet metal back bar located in position between the flanges of the front bar and bearing flat against said last mentioned bar, a ribbon stretched over the front face of said front bar and having its ends extending over the flanges and interposed between the bearing faces of the two bars, said flanges being bent down upon and overlapping said back bar for the purpose of retaining the latter and the ribbon in place, a rearwardly extending tongue formed integrally with the front bar at each end thereof and adapted to engage the adjacent end 110 of the back bar for the purpose of preventing endwise displacement of the latter, and means upon the back bar for attachment to 115

120

125

130

a garment, said means consisting of a pair of flat pliable sheet metal prongs secured upon the back bar and disposed perpendicularly to the rear face of the latter, said 5 prongs being adapted to be spread apart when inserted through a garment.

In testimony whereof I have signed my

name to this specification in the presence of two witnesses.

CHARLES F. GAUNT.
